UNITED STATES PATENT OFFICE.

ANDREW P. HAWN, OF GOODLAND, INDIANA, ASSIGNOR TO W. A. BRINGHAM & CO., OF CHICAGO, ILLINOIS.

CARBURETER.

SPECIFICATION forming part of Letters Patent No. 684,608, dated October 15, 1901.

Application filed November 30, 1900. Serial No. 38,237. (No model.)

To all whom it may concern:

Be it known that I, ANDREW P. HAWN, of Goodland, in the county of Newton and State of Indiana, have invented a new, useful, and 5 Improved Carbureter, of which the following is a full, clear, and exact description, reference being had to the accompanying drawings, forming a part of this specification, in which similar letters of reference in both figures indicate corresponding parts.

The object of my invention is to so construct a generating apparatus for generating gas for illuminating and other purposes from naphtha or other hydrocarbon oils that the 15 same may without the use of controlling-valves or other analogous mechanism act automatically to supply to the generator such quantity of naphtha as may be necessary to generate the volume of gas required to supply the burners in use at any given time, 20 whether one or more, and to maintain a uniform pressure at said burners.

To these ends my invention consists in providing a tank or other source of naphtha-supply under pressure in communication with a generator, one or more distributing-pipes in communication with the burners, and an auxiliary gas-receiver so connected with the generator-tank and distributing-pipes, respectively, that the pressure of the gas in the gas-receiver may, as it increases or diminishes through the use of gas at the burners, serve to increase or diminish the quantity of naphtha admitted to the generator by raising or 35 lowering its level therein, thus automatically varying the quantity of gas generated according to the amount used at the burners while maintaining a constant and uniform pressure at said burners, all of which is hereinafter 40 more particularly described and claimed.

In the accompanying drawings, Figure 1 is a side elevation, partly in section, of an apparatus embodying the features of my invention; and Fig. 2 is a like view showing a modified construction.

Referring to said drawings, *a*, Fig. 2, represents a gasolene-supply tank, which is preferably connected, by means of a pipe *b*, with an air-pump or other source of air-pressure, 50 while a supply-pipe *c* leads from the tank to a suitable gas generator or retort. In Fig. 1

the supply-tank is not shown; but it is obvious that the supply-pipe *c* may lead to a supply-tank in which pressure may be maintained either by means of an air-pump or by gravity 55 in the usual way. In the figure last named the supply-pipe *c* leads directly to the bottom of a vertically-arranged cylindrical reservoir *d*, which is surrounded near the bottom by an annular burner *e*, fitted closely thereto and having burner-openings *f* in the top for the escape of gas. A ring-shaped generator *g* also surrounds the part *d*, being located directly above the burner. Both generator and burner are protected by means of 60 an overhanging metal hood *h*, which is open at the bottom. A pipe *i* is extended from the top of the cylindrical reservoir *d* to the generator *g*. Leading outwardly from the generator *g* is a pipe *j*, upon the outer end of 65 which is secured a fitting *k*, provided with the usual needle-valve *l*, the counterparts of which are shown in section in Fig. 2 and correspondingly lettered. Beneath said needle-valve is an upwardly-bent tube *m*, open at 70 the top, said tube being arranged to communicate with the burner *e*, while preferably opposite thereto is a pipe *n*, leading from the generator *g* to a fitting *o*, having an upwardly-directed needle-valve *p* located beneath the 75 open mouth of a gas-distributing pipe *q*, having a suitable deflecting-plate *r* of any well-known construction at the bottom, so that an inflow of air may be induced, as hereinafter stated.

I prefer to provide a secondary receiver *s* for the reception of gas, the bottom of which is connected with the service-pipe *c* by means of a pipe *t*, while the top or some other portion thereof is connected with the reservoir *d* by means of a pipe *u*.

The operation of my improved device is as follows: Gasolene or other volatile hydrocarbon oil is forced through the service-pipe *c* into the bottom of the reservoir *d*. Heat is 95 then applied in any well-known way to the generator *g* until vapor is generated therein, when the valve *l* is opened, which causes a flow of vapor to the burner. The vapor being lighted, the flame continues to heat the 100 generator until a supply of gas accumulates in both the receivers *d* and *s*. The valve *p*

being opened, the gas is caused to flow into the distributing-pipe q . Should there be an insufficient number of burners in use to consume the gas generated, the pressure in the 5 reservoirs d increases, thereby forcing back the supply of naphtha and lowering its level in the bottom of the reservoir d until only a sufficient amount is present to supply the requisite demand at the required pressure. 10 I have found in actual practice that this action is automatic and that the apparatus is self-regulating to a degree. Should a number of burners be shut off, the back pressure of the gas within the gas or pressure reservoir or reservoirs acts at once to lessen the supply of naphtha at the generator, while the pressure upon the other burners remains unchanged.

While I prefer to use the reservoir s , it is 20 obvious that it may be dispensed with without varying the principle involved, in which case the supply-pipe c may be carried directly to the bottom of the reservoir d , as indicated in dotted lines, (shown at c' , Fig. 1,)

25 in which case I prefer to make said reservoir higher than it would be were it supplemented by the reservoir s , the object of which latter is merely to increase the volume of gas so stored.

30 In Fig. 2 I have shown a modification of said invention without in any way departing from the principle involved. In that construction the pipe c leads directly to the bottom of a reservoir d' , having an opening c' in 35 the bottom thereof, upon which reservoir is superimposed a larger reservoir d^2 , having an opening d^3 in the bottom, through which communication is established with the reservoir d' . A pipe v , having a coil w therein, is ex- 40 tended laterally from the bottom of the reservoir d' and thence after being coiled, as shown, upwardly to the bottom of the reservoir d^2 , the coil w serving as a generator. The pipe j is led from the top of the reservoir d^2 45 to the fitting k , having the needle-valve l . Beneath the valve-opening is placed a pipe x , communicating at the bottom with a burner x' , located beneath the generating-coil w . A pipe y , preferably coiled at z above the 50 burner, is led from the bottom of the reservoir d^2 to the valve-fitting o , beneath the distributing-pipe q . The tank a being subjected to air-pressure, the naphtha is caused to rise into the reservoir d' , the normal level being 55 substantially as shown. When in operation, the gas is generated in the pressure-regulating tank d^3 , from whence it passes through the pipe x to the burner, the flame from which heats the generator. The pressure in the ap- 60 paratus is obviously self-regulating, precisely as in that shown in Fig. 1, causing the amount of gas generated to conform to the demand therefor at the burners by causing the level of the naphtha in the generator to be raised or 65 lowered as a result of variation in pressure

in the reservoir d^2 , thereby maintaining a constant pressure at the burners. An advantage of this construction is that the burner is placed directly beneath the gas-reservoir, which serves to maintain the gas therein in 70 a heated state.

Having thus described my invention, I claim—

1. In an apparatus of the class described, the combination of a gas-generator, a source 75 of oil-supply under pressure, means for heating said generator, an enlarged gas-receiver in communication both with said generator and said source of oil-supply, and a gas-delivery pipe in communication with said gas-receiver, whereby the volume of gas within said enlarged receiver may serve as an elastic cushion to regulate the oil-supply at the burner and to impart a uniform pressure within the delivery-pipe, substantially as 85 specified.

2. In an apparatus of the class described, a source of oil-supply under pressure, a generator in operative communication therewith, means for heating said generator, an enlarged 90 gas-receiver having a capacity for holding a volume of gas in excess of the maximum demand thereon, said receiver being in communication with the generator-burner and a source of oil-supply respectively, and a gas-delivery pipe in communication with said enlarged gas-receiver, substantially as 95 described.

3. In an apparatus of the class described, a source of oil-supply, a generator or retort 100 in operative communication therewith, a supplemental gas-receiver in communication with the generator and source of oil-supply respectively, a gas-delivery pipe in communication with said gas-receiver, and a pipe and 105 burner for supplying a subflame to the generator, the whole being closed from the outer atmosphere except at the gas-delivery opening, substantially as described.

4. The combination with an oil-supply tank 110 and means for producing pressure therein, of a gas-generator, a gas-delivery pipe, means for heating said generator, and an interposed gas-receiver arranged to produce a back pressure of gas upon the retort proportioned to the 115 demand at the burners, said gas-receiver being located in operative proximity to the sub-flame of the generator, and a conduit leading from said receiver into contact with the sub-flame before final delivery to the service-pipe; 120 whereby the gas from the receiver may be superheated, substantially as described.

In testimony whereof I have signed this specification, in the presence of two subscribing witnesses, this 23d day of November, 1900. 125

ANDREW P. HAWN.
